UNITED STATES PATENT OFFICE.

WILLIAM M. CASWELL, OF WARREN, PENNSYLVANIA.

TROLLEY-WHEEL HARP.

No. 920,269.

Specification of Letters Patent.

Patented May 4, 1909.

Application filed June 8, 1908. Serial No. 437,361.

To all whom it may concern:

Be it known that I, WILLIAM M. CASWELL, a citizen of the United States, residing at Warren, in the county of Warren and State of Pennsylvania, have invented certain new and useful Improvements in Trolley-Wheel Harps; and I do declare the following to be a full, clear, and exact description of the invention, such as will enable others skilled in the art to which it appertains to make and use the same.

This invention relates to improvements in trolley wheel harps.

The object of the invention is to provide a trolley wheel harp having formed therein chambers adapted to contain lubricating oil, such chambers being provided with pockets so arranged as to prevent the escape of oil, no matter what position the harp may assume.

A further object is to provide a device of this character having arranged therein an improved construction of trolley wheel bearings, and means in said bearings to feed the oil thereto from the oil chambers in the harp.

With these and other objects in view, the invention consists of certain novel features of construction, combination and arrangement of parts as will be described and particularly pointed out in the appended claims.

In the accompanying drawings, Figure 1 is a side view of a trolley wheel harp constructed in accordance with the invention; Fig. 2 is a plan view of the same; Fig. 3 is a vertical sectional view through one side of the harp and the bearing blocks and journals of the trolley wheel; Fig. 4 is a transverse sectional view taken on the line with the center of the trolley wheel journals; Fig. 5 is a vertical longitudinal sectional view through the center of the harp with the wheel removed; Fig. 6 is a detail plan view of the wheel and its journals; and Fig. 7 is a detail perspective view of one of the journal boxes removed from the harp showing the manner of fastening the lubricating wick thereto.

Referring more particularly to the drawings, 1 denotes the harp having on one end a socket, 2, to receive the end of the trolley pole to which the harp is secured in any suitable manner. The forks, 3, of the harp are provided on one side with lateral projections, said forks and projections being hollow to provide oil chambers, 4, which are extended toward the socket end of the fork and form pockets, 5, which are partly separated from the cham-

bers, 4, by partitions, 6. The forks are provided with squared seats, 7, which open through one side of the forks and adapted to receive bearing blocks, 8, which are removably arranged therein to receive the journals 60 of the trolley wheel. To one side of the bearing block seats, 7, and adjacent to the partition, 6, is formed a passage, 9, which is designed to permit the insertion of oil into the chambers, 4.

The side of the harp opposite to the extensions which form the oil chambers is flat and on said flat side are pivotally mounted cover plates, 10, said plates being pivoted at their lower ends and provided at their opposite 70 ends with hooks, 12, adapted to be engaged with fastening lugs, 13, formed on the upper ends of the forks, as shown. The lugs, 13, and hooked ends of the cover plates, 10, are provided with alined passages, 14, adapted 75 to receive cotter pins, 15, or other suitable fastening devices whereby the cover plates are held in operative position to close the upper open ends of the oil chambers and seats of the bearing blocks. On the inner edges of 80 the cover plates, 10, are formed laterally projecting inwardly curved guard flanges, 16, which, when the cover plates are in a closed position, are adapted to project into close proximity to the sides of the trolley wheel 85 and serve to prevent the trolley wire from catching on the flat sides of the forks when the wheel becomes disengaged from the wire.

The trolley wheel, 17, may be of the usual or any desired construction and in the hub of 90 the same is rigidly secured a shaft or axle, 18, on each end of which are formed cylindrical heads or journals, 19, adapted to enter and turn in the bearing boxes, 8. The axle or shaft, 18, is reduced between the journals, 19, 95 and the adjacent ends of the harp, said reduced portion being adapted to engage notches or recesses, 20, formed in the opposite inner walls of the forks, said notches being arranged in the center of the seats 7 for 100 the bearing boxes.

The bearing blocks 8 may be formed of any suitable metal and are of rectangular or other suitable shape and provided with a centrally disposed circular bearing aperture, 21. In 105 two of the meeting edges of the block are formed grooves or channels, 22, adapted to receive a lubricating wick, 23, one end of which is secured in a hole, 24, formed through one corner of the block and communicating 110

with one of the grooves, 22, as shown. In the other groove of the block is formed an elongated opening, 25, with which the wick is engaged when arranged in the grooves. 5 The portion of the wick which enters the opening, 25, is adapted to engage the upper side of the bearing head or journal of the trolley wheel, and in this manner applies the oil to the bearing. The free end of the wick is 10 adapted to project down into the oil chamber, from which it takes up the oil by capillary attraction.

By providing a trolley wheel harp with oil chambers and blocks constructed and arranged as herein shown and described, the oil will be prevented from escaping from the chambers, no matter what position the harp may assume. By providing the bearing blocks and oil conducting wicks arranged as 15 herein shown and described, a continuous and uniform supply of oil is applied to the journals of the trolley wheel, thus keeping the same properly lubricated at all times.

From the foregoing description, taken in 20 connection with the accompanying drawings, the construction and operation of the invention will be readily understood without requiring a more extended explanation.

Various changes in the form, proportion 25 and the minor details of construction may be resorted to without departing from the principle or sacrificing any of the advantages of the invention as defined in the appended claims.

Having thus described my invention, what I claim as new and desire to secure by Letters-Patent, is:

1. A trolley wheel harp having oil chambers and pockets in its forks, bearing block 30 seats formed in said chambers, bearing blocks arranged in said seats, said blocks having grooves formed in their edges, one of said grooves opening through and communicat- 35 ing with the bearing opening formed in the block whereby an oil passage is provided, and means whereby oil is conducted to said passage from the pockets and chambers in the harp, substantially as described.

2. In a trolley wheel harp, hollow forks having arranged therein an oil chamber and 40 an oil receiving pocket, seats formed in said chambers, bearing blocks arranged in said seats, a trolley wheel, a shaft arranged in said trolley wheel and projecting laterally therefrom, bearing heads or journals formed 45 on the outer ends of said shaft to engage said bearing blocks, and lubricating wicks connected to said block and projecting into said oil chambers whereby the oil is conducted to said journals, substantially as described.

3. In a trolley wheel harp, hollow forks having formed therein oil chambers and oil receiving pockets, seats formed in said chambers, bearing blocks arranged in said seats, means to conduct the oil from said oil chambers and pockets to said bearing blocks, a trolley wheel having journals to engage said blocks, pivoted cover plates arranged on said forks to cover and close the oil chambers and seats therein, and inwardly curved guard 50 flanges formed on the inner edges of said cover plates to prevent the trolley wire from catching into the forks of the harp when the wheel is disengaged from the wire.

4. A trolley wheel harp having oil chambers and pockets in its forks, bearing block 55 seats formed in said chambers, bearing blocks arranged in said seats, said blocks having grooves formed in their edges, one of said grooves opening through and communicat- 60 ing with the bearing opening formed in the block whereby an oil passage is provided, and means whereby oil is conducted to said passage from the pockets and chambers in the harp, substantially as described.

In testimony whereof I have hereunto set my hand in presence of two subscribing witnesses.

WILLIAM M. CASWELL.
